(57) **CLAIM**

The ornamental design for a water shut-off valve tool, as shown and described.

DESCRIPTION

FIG. 1 is a front top perspective view of a water shut-off valve tool showing the claimed design, the back top perspective view is identical;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.
